CLAIM

The ornamental design for a hair brush head, as shown and described.

DESCRIPTION

FIG. 1 is a perspective view of a hair brush head constructed in accordance with the teachings of the present invention. FIG. 2 is a side view thereof, the opposite side being a mirror image thereof.

FIG. 3 is another side view thereof rotated 90 degrees from the FIG. 2 orientation, the opposite side being a mirror image thereof.

FIG. 4 is a top end thereof; and,

FIG. 5 is a bottom end thereof.

It will be further understood that the broken line showing the handle throughout the drawings is for illustrative purposes only and forms no part of the subject invention.
